UNITED STATES PATENT OFFICE.

WILLIAM T. SCHNEEWEISS, OF ST. LOUIS, MISSOURI.

DEVICE FOR REMOVING SLIP-COVERS.

1,340,413.

Specification of Letters Patent. Patented May 18, 1920.

Application filed January 21, 1920. Serial No. 353,044.

To all whom it may concern:

Be it known that I, WILLIAM T. SCHNEEWEISS, a citizen of the United States of America, residing at the city of St. Louis, State 5 of Missouri, United States of America, have invented a certain new and useful Device for Removing Slip-Covers, of which the following is such a full, clear, and exact description as will enable anyone skilled in 10 the art to which it appertains to make and use the same, reference being had to the accompanying drawings, forming part of this specification.

Heretofore receptacles with slip covers have been provided with a cam mechanism 15 for removing the cover. One of the objections to this prior construction is that in order to sufficiently separate the body and the cover of the receptacle, it is necessary 20 for the cam to project below the edge of the cover, so that when carelessly replaced the flange on the body of the receptacle will pass below the cam and thus render the device inoperative. Another objection is that 25 the leverage of the device is so small as to render the operation of the device difficult when the cover fits tightly upon the body. Still another objection is that the device is so large as to be clumsy and unsightly. 30 The object of my invention is to provide a device of the class indicated in which the above stated objections will be overcome.

In the accompanying drawings which illustrate one form of device made in accordance 35 with my invention, Figure 1 is a side elevation showing the complete receptacle, Fig. 2 is a side elevation of a portion of the receptacle showing the parts in a different position, Fig. 3 is a top plan view of 40 a portion of the receptacle, Fig. 4 is a horizontal section, and Fig. 5 is a vertical section.

The receptacle to which my device is applied consists of a body portion 10, and a 45 slip cover 11. These may be of any suitable form. In the drawings I have shown them as constituting a blackening box of ordinary form. The body 10 of the receptacle is provided, intermediate of its height, with a 50 flange 12 preferably formed by bending a portion of the metal outwardly. Formed integral with the cap 11 is a lever support 13 which is bent up parallel with the flange of the cover 11. 14 is a lever which is piv-

oted to the support 13 by means of a rivet 55 15. The rivet 15 is so situated in the lever 14 as to provide a short and long end. The short end of the lever is provided with an inturned portion 16 adapted to strike against the flange 12 and thus separate the body 60 and cover of the can. The long end of the lever 14 is provided with an outwardly bent portion 17, preferably doubled, which provides a finger piece for operating the lever. As the lever conforms to the curvature of 65 the box or can it may be made of any suitable length so as to secure the desired amount of leverage without increasing the bulk of unsightliness of the device. The upper part of the lever support 13 is bent over to form 70 a stop 18 adapted to strike against the upper edge of the lever 14 and is so situated with relation to the lever that the inturned end 16 cannot pass below the lower edge of the lid 11. In this way the flange 12 is prevented 75 from passing between the end 16 and the edge of the can.

The operation of my device will be evident. When the parts are in their normal position as shown in Fig. 1 of the drawings, 80 it is only necessary to press upwardly on the finger piece 17 in order to cause the inturned end 16 to press against the flange 12 and separate the body and cover of the receptacle as shown in Fig. 2.

Having fully described my invention, what I claim as new and desire to secure by Letters Patent of the United States is:

1. The combination with a receptacle, of a slip cover therefor, one of said parts being 90 provided with a projection, a lever pivotally carried by the other of said parts and provided at one side of its pivot with a portion adapted to contact with said projection and at the other side with a finger piece, and 95 a stop projecting over said lever and adapted to contact with the upper edge of said lever to prevent its either end from moving into position to render the device inoperative.

2. The combination with a receptacle, of a slip cover therefor, one of said parts being provided with a projection and the other with an integral lever support, a lever pivoted to the outside of said support and 105 adapted to engage with said projection to remove the cover, and a stop formed integral with said lever support and engaging

100

105

- with the upper edge of the lever for preventing the movement of either end of said lever into position to render the device inoperative.
- 5 3. The combination with a receptacle having a curved periphery and provided intermediate of its height with a projecting flange, of a slip cover therefor provided with an integral lever support, a lever pivoted to said support and conforming to the curvature of the receptacle, the ends of said lever being of unequal length, the short end of said lever being provided with an inturned portion adapted to engage with said flange to remove the cover, and the long end 15 being provided with an outwardly projecting portion forming a finger piece, and a stop formed from a bent over portion of said lever support for engaging with the edge of the lever to prevent said inturned portion 20 from projecting beneath the edge of the cover.

In testimony whereof, I have hereunto set my hand and affixed my seal.

WILLIAM T. SCHNEEWEISS. [I. S.]
